MACHINE FOR LOADING WRAPPERS OR
POUCHES

Isaac A. Hardy, Evansville, Ind., assignor, by
mesne assignments, to E. I. du Pont de Nemours
& Company, Wilmington, Del., a corporation of
Delaware

Application January 9, 1930, Serial No. 419,701

18 Claims. (Cl. 226—2)

The present invention relates to the packaging of materials in wrappers or pouches. The particular object of the invention is to provide a machine for inserting cigars in pouches such, for example, as tubular containers or envelopes, and while the machine is designed for this particular purpose and with this object in view, it is not limited or confined to that operation alone, the principles of the invention being adaptable for other uses.

The machine is illustrated in conjunction or combined with a cigar banding machine, so that the banded cigars as they issue from that machine are automatically inserted in the pouches. The machine is also shown as intended for the insertion of the cigars in tubular envelopes which are sealed at one end, although the principles of the invention may be used in packaging materials in other forms of envelopes.

The machine may also be combined with mechanism for folding and sealing the wrapper after the insertion of the cigar, but these additions to the machine are not illustrated or described.

The machine is especially adapted for the handling of sealed envelopes or wrappers made of thin transparent, moistureproof material such, for example as moistureproof regenerated cellulose sheeting, which material is delicate and easily torn, so that special features are necessarily incorporated in the machine for this purpose, but it will be understood that the invention is not limited to such restricted fields but may be employed in other fields and for other uses.

The invention is illustrated in considerable detail but it will be apparent that changes, modifications or improvements may be made therein without altering the essential features of the invention or changing its principles.

In the drawings, in which the best known or preferred form of the invention is shown;

Figure 1 is an end elevation of the machine;

Figure 2 is a plan view thereof with the magazine removed;

Figure 3 is a transverse section on the line 3—3 of Figure 2;

Figure 4 is a longitudinal section along the line 4—4 of Figure 2 taken at the point of loading;

Figure 5 is a section on the line 5—5 of Figure 2 taken through the center of the machine;

Figure 6 is a section on the line 6—6 of Figure 2;

Figure 7 is a section on the line 7—7 of Figure 2 showing the driving mechanism;

Figure 8 is an enlarged horizontal section taken at the mouth of the tube or container showing

the combined guiding means for the cigar and spreader for the mouth of the tube;

Figure 9 is an enlarged horizontal section through the magazine on the line 9—9 of Figure 4;

Figure 10 is an enlarged view of the lower portion of the mechanism shown in Figure 4;

Figure 11 is a cross section through an unfilled container; and

Figure 12 is a cross section through a filled container.

In the drawings the cigars are shown at 1 and the container or pouch is shown at 2. The cigars are delivered from a banding machine (not shown) which is to be located at the left of the machine as shown in Figure 2, being delivered in a file or row, with the trade-marked or decorative side of the bands uppermost, along a rail or guideway 3 and along the top of the table 4, a thin spacer plate 5 being provided to elevate the cigars slightly above the surface of the table. The cigars are moved over by the delivery mechanism of the banding machine against a stop plate 6 which is spaced from the end of the rail 3, a distance equal approximately to the thickness of a single cigar, so that the latter may be moved from the row into the loading mechanism.

The table 4 is supported upon vertical pillars 7 from the base 8 of the machine.

Pouch feeding mechanism

30

The containers 2 are elongated flattened pouches having a folded and sealed end 9 and folded or plicated sides 10. On one of the panels is located the longitudinal seam 11 which, in order to display the bands properly, should be located on the underside of the container when the cigar is inserted.

The pouches are assembled in stacks which are inserted in a vertically movable magazine which is indicated in general by the numeral 15, care being taken to place the seams 11 uppermost so that in the subsequent reversal of the pouch by the machine the seam will be underneath at the time the cigar is inserted.

The magazine is composed of two spaced end plates 16 which are provided with cut outs 17 facing each other at a distance slightly greater than the length of a pouch so as to permit the passage of the pouch. Light metal strips or shelves 18 project beneath the cut out portions of the plates to support the stack of pouches by the ends thereof, permitting them to be withdrawn one at a time from the underside of the stack. The plates 16 are provided with vertical

45

35

40

45

50

55

extensions 18 which are secured to the cross head 20 near the corners of the stack and at the ends thereof are located the groups of vertical pillars 21 connected at their upper ends by the plate 22.

- 5 The magazine is designed to be raised and lowered by the apparatus during the operation of the machine and in timed relation to the balance of the apparatus and particularly to the operation of a transfer wheel to be described so that 10 a single pouch or container is removed from the base of the stack. For this purpose the cross head 20 is connected by means of two spacer blocks 25 to a vertically movable slide 26 which reciprocates in guideways 27 in two vertical posts 15 28 rising from the base plate 4. To the rear of the slide 26 is secured the bracket 30 which carries a roller 31 on the end thereof directly over the main or cam shaft 32, the latter being mounted in brackets 33 rising from the base plate. 20
- 20 On the shaft 32 beneath the roller 31 is secured a cam 34 which lifts the magazine periodically. At the lowermost point of its movement the magazine is supported by means of fingers 35 which are attached to the front of the cross head 20. 25
- 25 the lower ends of the fingers resting upon bearing rings 36 set in an intermittently rotating drum or transfer wheel which is indicated by the numeral 38. 20

Transfer drum

- 30 The drum 38 which constitutes a carrier for the container is secured to the projecting end of a horizontal shaft 40 which is mounted in a front bracket 41 and a rear bracket 42. On the drum 38 are provided the four equally spaced arms 44 which are arranged to be brought successively in register with the underside of the stack of pouches in the magazine. The faces of the arms are flattened as shown for holding the pouches by their panels. Extending through the drum 40 and through the arms are passages 45, the outer ends of which are closed by plugs 46. Radial passages 47 extending from the passages 45, open onto the face of the drum, being located at sufficient intervals to engage and hold the pouches 45 as will be described.

Pressed against the rear face of the drum by a spring 49 and keyed upon a sleeve 48 on the bracket 41 is a plate 50 in the face of which is formed the semi-circular groove or passage 51 which registers with the ends of the passages 45 during the 180° of revolution of the drum, in which the arms 44 are moved from their position beneath the stack of pouches to cigar loading position. A pipe 52 is carried upon the plate 50 and is in communication with the groove 51. The other end of the pipe is connected to a header 53 to which is connected a main suction pipe 54 leading from a source of vacuum or partial vacuum. By the means described suction is created 55 in the passages 45 to seize a pouch from the bottom of the stack when the latter is lowered and retain it against the flattened face of the drum until it is carried around to the lower side of the drum in the position to receive the cigar. 60

65 As the drum moves from the loading position, the vacuum is released by the movement of the passage beyond the end of the groove 51. The operation of the machine is so timed that the magazine will be lowered against the uppermost 70 face of the drum and sufficiently close to the openings 47 to permit the lowermost pouch to be removed from the stack, the cam 34 raising the magazine in timed relation to the step by step rotation of the drum so that the pouch is with- 75 drawn.

Pouch opening mechanism

When the pouch, which is held against the lower face of the drum at the loading position shown in Figure 4 is to receive the cigar, it must be opened and held in open position to a sufficient extent to permit the entrance of the cigar. This operation is performed by a small reciprocating sucker head which is shown at 60, being in the form of a stem having a passage 61 therein opening on its upper face through a plurality of small passageways 62. The sucker head is slidably mounted in a tube 64 located in the table 4 near the mouth of the pouch and moves from a position flush with the surface of the table to a position contacting with the underside of the pouch where the suction seizes the mouth of the pouch and spreads it on the downward movement of the sucker head. In its vertical movement the sucker head is guided by the pin and slot 65. 10

15 The lower end of the passage 61 communicates by a flexible hose 66 with a pipe 67, leading to the suction box 53. The surface of the suction head is relatively small so that in the practical operation of the machine the vacuum may remain on at all times, the force exerted by the head being sufficient to open the pouch but not interfering with the release of the filled pouch. 20

25 The head 60 is carried upon a pin 69 movable in a slot 68 and projecting from the end of a lever arm 70 pivoted on a bracket 71 secured to the underside of the plate 4. The lever is normally in the position in which the sucker head is flush with the table, being yieldingly held in that position by a coil spring 72. The lever is 30 actuated to raise the sucker head momentarily by a vertically movable plunger 74 having a roller 75 on its lower end engaging the lever, and a roller 76 on its upper end which is located in the path of a cam 78 on the cam shaft 32. The 35 plunger is guided in a sleeve 79 passing through the plate 4 and is kept in alignment by a key and keyway 79a. 40

Cigar loading mechanism

45 In order to insure the entrance of the cigar in the mouth of the pouch and to prevent the band from catching on the edge of the pouch, the machine has incorporated with it a combined spreader for the mouth of the pouch and guide 50 for the cigar. This instrumentality may be in a number of forms, but a form which has been found to be satisfactory is in the nature of a funnel made in two parts, each of which is pivoted so as to spread apart during the passage of the 55 cigar. The point or apex of the funnel is designed to enter the mouth of the pouch and spread it fully open to receive the cigar. This mechanism completes the opening of the pouch which has been commenced by the operation of the 60 sucker, and spreads the folds 10 along the sides of the pouch so that a pouch can be made to fit the cigar snugly. 65

The spreader or expanding funnel is shown in detail in Figure 8 and to the left in Figure 10. 70 It is located on the table 4 between and in alignment with the lowermost position of the drum and the forward cigar. It consists of two oppositely positioned scoop shaped plates or blades 80 which are concave in cross section and provided with rounded ends which are directed toward the mouth of the pouch. When in its closed or non-feeding position as shown in full lines in Figure 8 the pointed ends are in contact and are so located as to clear the mouth of the 75

pouch as it is brought around by the transfer drum. The edges of the blades are curved so that they can be moved in the manner to be described.

5 Each blade 80 is a part of or secured to a lug 81 by which it is pivoted on a vertical pin 82 on the table. Coil springs 83 on the pins are attached to the blades and to an adjustable collar 84 fixed on the upper end of the pin. Stops 85 limit the forward movement of the blades and 10 stops 86 their rearward movement.

15 As is shown in Figure 8, the opening movement of the blades 80 to the dotted line position, causes the forward ends of the blades to enter the open mouth of the tube and spread it to permit the entrance of the cigar into the tube. The movement of the spreaders or blades is caused by the passage of the cigar, the forward end of the cigar striking against the forward ends of the blades 20 and moving them as described, the concave cross section of the blades serving to guide the cigar with precision into the pouch, the panels of which are held by the transfer wheel and by the sucker head. After the cigars have passed the spreader 25 it is moved by the springs to its normal position.

30 The movement of the cigar is performed in timed relation to the intermittent movement of the transfer wheel and the sucker head by means of a reciprocating plunger 90 which is adjustably secured by set screw 91 in a head 92. This head is attached to a slide 94 movable in slideways formed in a bracket 95 attached to the underside of the table 4. A pin 96 is secured to the underside of the slide and is connected by link 97 to one end of a lever 98, pivoted at 99 to the underside of the table. The opposite end of the lever is connected by link 100 to a pin 101 depending from a slide bar 102 carried at its forward end in a guiding bracket 103 attached to the undersurface 40 of the table 4. Near the rear end on the sliding bar is mounted a roller 105 which is received in a cam groove or track 106 on the upper face of a revolving cam 107 carried by and connected to a vertical shaft 108 in a vertical bearing 109 on the table. The end of the sliding bar is provided with a slot 110 which is receivable over the shaft 108, by which the slide bar is guided in conjunction with the bracket 103. The central portion of the slide bar is also provided with a slotted portion 111 at the point where it intersects the sleeve 79.

45 It will be observed that the operation of the parts just described moves the forward cigar from its position at the head of the row or file through the spreader and into the mouth of the pouch, the movement of the plunger being continued until the cigar is fully seated in the pouch against a stop 112 on the table 4 (Figure 10). The cigar supporting surface may be grooved as shown at 113 to guide the cigar in its forward movement and an extension 114 may be provided to hold the cigar from tipping downwardly.

Discharging mechanism

50 The loaded pouch is then removed from the position in which it was filled, this operation being performed as the feed drum is moved forward so that the vacuum holding the upper side of the pouch is released by the movement of the passage 45 out of alignment with the channel 51. The removal of the cigar is performed by a pusher 129 which is fixed to the forward end of a slide 121 mounted in guideways 122 on the top of the table 4. Attached to the slide is a bracket 123 55 having a roller 124 at the side of the cam shaft

32. A cam 125 on the shaft moves the slide at the proper intervals and for the distance required to move the loaded pouch out of its loading position. A spring 136 attached to the slide and to the bracket 138 returns the slide after the dis- 5 charging operation.

As the loaded pouches are moved by the operation of the discharge mechanism, the ends of the pouches are guided in a longitudinal groove 140 in the face of the stop 112, this groove extending the length of the stop except where it is cut away as shown at 141 to permit the folded end of the pouch to move downwardly as the cigar is moved into it.

15 As the loaded pouches are moved forward over the table they are held down by two rails 145 spaced above the table and pivoted on the lower ends of posts 146 which are in turn supported by a cross bar 147 secured upon an upright 148 rising from the table. The ends of the rails 150 20 may extend to or near the periphery of the transfer drum in alignment with the rings 36 to insure the stripping of the loaded pouches from the transfer drum.

25 The machine may be associated with any suitable folding or folding and sealing device for closing the open end of the pouch and completing the sealing operation, but this mechanism may be of varied forms and has not been illustrated in connection with the present invention. 30

Driving mechanism

35 The machine is driven by any suitable means, that illustrated comprising a pulley 152 on a drive shaft 153 mounted in bearings 154 on the table 35 4. The pulley and drive shaft may be connected or disconnected at the will of the operator by means of a clutch 155, the operation of which is controlled by a clutch shifting lever 156 pivoted at 157 to a bracket 158 extending from the table 40 4. The lower end of the lever 156 is pivoted to a rod 159 which is connected to an operating rod 160 movable in bearings 162 on posts 7. The rod 160 is moved by means of a cam 163 mounted upon a transverse shaft 164 journalled in bearings 45 165 at the front of the machine, and having operating handles 166. The cam 163 is arranged to bear against a vertical wall of a bracket 167 connected to the rod 160.

50 The driving shaft 153 may also be moved by means of a hand wheel 168 attached to the end thereof.

55 Located on the shaft 153 is a pinion 170 which engages a gear 171 freely rotatable on the shaft 40 of the transfer drum at one side of the bracket 42. Carried on the face of the gear 171 is the pivoted pawl 172 which is moved inwardly by the spring 174 also mounted on the gear (Figures 4 and 7). Fixed to the shaft 40 is the indexing wheel 176 which is provided with four 60 notches 177 corresponding to the four arms 44. The shaft 40 is designed to be rotated one step for each complete revolution of the gear 171 and this operation is performed by providing the fixed disk 180 which loosely surrounds the hub 65 of the indexing wheel and lies against its face, being attached to the bracket 181 secured to the table. The end of the pawl 172 rides on the outer edge of the disk 180 which keeps it out of engagement with the several notches except during one quarter of its revolution. At its upper edge the disk is cut away as shown at 182 for a sufficient distance to enable the pawl to engage a notch 177 and move the wheel 176 and the shaft 70 75 until the pawl is again raised out of engagement.

ment with the notch by the contour of the disk. By the mechanism described the transfer wheel is given its one-quarter intermittent movement while the remainder of the machine is completing 5 a single operation.

The transfer wheel is kept in stationary position during the operation of the loading mechanism by means of a spring pressed roller 183 which engages with one of four equally spaced 10 notches in a disk 184 secured to the shaft 40.

The gear 171 engages and drives a gear 185 on the main or cam shaft 32 and the cam shaft is provided with a bevel pinion 186 which drives a like bevel pinion 187 on the vertical shaft 108 15 which rotates the plunger cam 107.

Operation

It is believed that the operation of the machine will have been made clear as the description of the several parts has been given. The magazine being filled with the pouches, individual pouches are removed from the bottom of the stack in the magazine, as the latter is raised and lowered by the cam 34, by the operation of 25 the suction in the transfer wheel. As the wheel revolves it brings the individual pouches to position at the lower side of the wheel and as the wheel is stationary, the sucker 60 is moved upward, seizes the mouth of the pouch and on its 30 downward movement opens it as shown in Figure 4, this operation occurring in time to clear the end of the cigar.

The forward cigar is then fed into the pouch through the spreader or funnel which is operated 35 by the passage of the cigar and spreads the mouth of the pouch to its fully opened position. The plunger then withdraws and the transfer wheel moves to its next position, at which time the ejecting plunger operates to move the cigar out 40 of the loading position. The suction on the several faces of the transfer wheel is continued for 180° from the point at which the pouch is removed from the magazine until the cigar is loaded in the pouch and is ready for removal.

45 It will be seen that there has been devised a useful and efficient machine which will take the single pouches from the stack, open them and fill them with cigars. The machine is entirely automatic and being run in timed relation to the output of a banding machine, it will effectively load the output of that machine in the prepared pouches. Various improvements or alterations 50 may be made on the machine and the principles of the machine may be employed in other or specifically different forms. The problem of filling the light, fragile regenerated cellulose pouches has been solved, although the machine is not in any manner confined to that particular use.

60 The machine is illustrated as holding the pouches in a horizontal position. It is apparent, however, that the novel features of the machine are adaptable to operate on containers to be held in a vertical position with an open end up 65 for loading.

It will be understood that, as this machine is a pioneer machine for the purposes set forth, the appended claims are not to be limited in scope to duplicates of the mechanism shown, for it is possible to embody the principles of the invention in other forms than that shown.

When the word "pouch" or "container" is used in the specification and claims it is intended to include all sorts of envelopes or wrappers, either 70 in the exact form shown, open at both ends or at

one end only and in tubular, plicated or any other cross section to hold a single cigar or a group of cigars, or any other materials. Neither is the machine limited to the packaging of cigars, and where the term "cigars" is used in the specification and claims, it is intended to include materials generally. 5

What is claimed is:

1. A machine of the character described comprising suction holding means movable into contact with opposite sides of a pouch-like container and separable to open one end thereof, a combined guide and spreader comprising a pair of opposite blades having tapering ends normally in contact with each other and movable into the 15 mouth of the container by the passage of a load therebetween, means whereby movement of said blades into the mouth of the container causes said blades to separate and to hold said mouth in open position, and means to load the container while held in open position.

2. A machine of the character described comprising suction holding means movable into contact with opposite sides of a pouch-like container and separable to open one end thereof, a 25 funnel comprising two concave oppositely pivoted blades having tapering ends normally in contact with each other and adapted to enter the mouth of the container by the passage of a load therebetween, means whereby movement of said blades into said mouth causes said tapering ends to spread and hold said mouth open, and means to load the container while held in open position.

3. A machine of the character described comprising suction holding means movable into contact with opposite sides of a pouch-like container and separable to open one end thereof, and a combined guide and spreader comprising a pair of opposite blades having tapering 40 ends normally in contact with each other and movable into the mouth of the container by the passage of a load therebetween, and means whereby movement of said blades into the mouth of the container causes said blades to separate 45 and to hold said mouth in open position.

4. A machine of the character described comprising suction holding means movable into contact with opposite sides of a pouch-like container and separable to open one end thereof, a 50 funnel comprising two concave oppositely pivoted blades having tapering ends normally in contact with each other and adapted to enter the mouth of the container by the passage of a load therebetween, and means whereby movement of said blades into said mouth causes said tapering ends to spread and hold said mouth open.

5. In a machine, the combination of a magazine for pouches, an intermittently movable 60 transfer drum having suction openings on its face, means to maintain a partial vacuum thereon during a portion of the rotation of the drum, means to feed pouches on to the drum, means for opening the pouches while so held, a loading 65 device operable while the pouch is opened, and means to relieve the vacuum after the loading operation and to remove the loaded pouch.

6. In a machine for the purposes set forth the combination of suction means for holding a container, means for moving a cigar longitudinally into the container, and an expandible spreader comprising yielding, oppositely pivoted blades located in the path of the cigar and having normally converging ends adapted to enter the end 70

of the container, movement of said blades into said container causing said blades to expand, the spreader being movable into the container by the passage of the cigar.

5 7. In a machine for the purposes set forth, the combination of suction means for holding a container, means for moving a cigar longitudinally into the container, and a pair of oppositely pivoted yielding blades normally held with their ends directed toward the mouth of the container and movable in diverging arcs so that the ends of the blades spread as they enter the mouth of the container, the spreader being movable into the container by the passage of the cigar therebetween.

10 8. In a machine for the purposes set forth, the combination of suction means for holding a container, an expansible spreader and guide comprised of a pair of yieldingly mounted blades normally held with the ends directed toward the mouth of the container and movable in diverging paths so that they spread as they enter the mouth of the container, and means for moving a cigar through the spreader, the spreader being movable into the container by the passage of the cigar therebetween.

15 9. In a machine for the purposes set forth, the combination of means for holding a container, an expansible spreader and guide comprised of a pair of yieldingly mounted blades normally held with the ends directed toward the mouth of the container and movable in diverging paths so that they spread as they enter the mouth of the container, means for moving a cigar through the spreader, the spreader being movable into the container by the passage of the cigar therebetween, and suction means for opening the container to receive the spreader.

20 10. In a machine for the purposes set forth, the combination of means for holding a container, an expansible spreader and guide comprised of a pair of yieldingly mounted blades normally held with the ends directed toward the mouth of the container and movable in diverging paths to enter the mouth of the container, means for moving a cigar through the spreader, the spreader being movable into the container by the passage of the cigar therebetween, and suction means contacting opposite sides of the container and separable to open the same to receive the spreader.

25 11. In a machine for the purposes set forth, the combination of suction means for holding a container, an expansible spreader and guide comprised of a pair of yieldingly oppositely pivoted blades normally held with the ends directed toward the mouth of the container and movable in diverging arcs so that they expand as they enter the mouth of the container, and means for moving a cigar through the spreader, the spreader being movable into the container by the passage of the cigar therebetween.

30 12. In a machine for the purposes set forth, the combination of suction holding means movable into contact with opposite sides of a pouch-like container and separable to open one end thereof, loading means for inserting a load into the container, and an expansible spreader comprising yielding oppositely-pivoted blades located in the path of the load and having normally converging ends adapted to enter the end of the container, movement of said spreader into said container causing said spreader to expand, the spreader being movable into the container by the action of the loading means.

35 13. In a machine for the purposes set forth, the combination of suction holding means movable into contact with opposite sides of a pouch-like container and separable to open one end thereof, loading means for inserting a load into the container, a pair of oppositely-pivoted yielding blades normally held with their ends directed toward the mouth of the container and movable in diverging arcs so that the ends of the blades spread as they enter the mouth of the container, the spreader being movable into the container by the passage of the load therebetween.

40 14. In a machine for the purposes set forth, the combination of suction holding means movable into contact with opposite sides of a pouch-like container and separable to open one end thereof, an expansible spreader and guide comprised of a pair of yieldingly mounted blades normally held with the ends directed toward the mouth of the container and movable in diverging paths so that they spread as they enter the mouth of the container, and means for loading the container through the spreader, the spreader being movable into the container by the passage of the load therebetween.

45 15. In a machine for the purposes set forth, the combination of means for holding a container, an expansible spreader and guide comprised of a pair of yieldingly mounted blades normally held with the ends directed toward the mouth of the container and movable in diverging paths so that they spread as they enter the mouth of the container, means for loading the container through the spreader, and suction means for opening the container to receive the spreader, the spreader being movable into the container by the passage of the load therebetween.

50 16. In a machine for the purposes set forth, the combination of means for holding a container, an expansible spreader and guide comprised of a pair of yieldingly mounted blades normally held with the ends directed toward the mouth of the container and movable in diverging paths to enter the mouth of the container, means for loading the container through the spreader, the spreader being movable into the container by the passage of the load therebetween, and suction means contacting opposite sides of the container and separable to open the same to receive the spreader.

55 17. In a machine for the purposes set forth, the combination of suction holding means movable into contact with opposite sides of a pouch-like container and separable to open one end thereof, an expansible spreader and guide comprised of a pair of yieldingly oppositely-pivoted blades normally held with the ends directed toward the mouth of the container and movable in diverging arcs so that they expand as they enter the mouth of the container, and means for loading the container through the spreader, the spreader being movable into the container by the passage of the load therebetween.

60 18. In a machine, the combination of a magazine for pouches, a movable transfer drum having suction openings on its face, means to maintain a partial vacuum thereon during a portion of the rotation of the drum, means to feed pouches on to the drum, means for opening the pouches while so held, a loading device operable while the pouch is opened, and means to relieve the vacuum after the loading operation and to remove the loaded pouch.

ISAAC A. HARDY.
